UNITED STATES PATENT OFFICE.

MARSHALL B. LLOYD, OF MENOMINEE, MICHIGAN.

METHOD OF PRODUCING WOVEN REED ARTICLES.

1,243,079.

Specification of Letters Patent. Patented Oct. 16, 1917.

Application filed July 17, 1916. Serial No. 109,714.

To all whom it may concern:

Be it known that I, MARSHALL B. LLOYD, a citizen of the United States, and a resident of Menominee, county of Menominee, and 5 State of Michigan, have invented a certain new, useful, and Improved Method of Producing Woven Reed Articles, of which the following is a specification.

My invention relates generally to the manufacture of reed articles and relates more particularly to the manufacture of reed fabric, and also to its application to supporting frames.

Cross reference is hereby made to applicant's co-pending applications each entitled Method of producing woven reed articles and bearing serial numbers and filing dates as follows: Serial No. 146,909, filed February 6th, 1917; Serial No. 146,910, filed February 6th, 1917; Serial No. 149,614, filed February 19th, 1917; which applications disclose and claim certain subject matter which is herein disclosed but not claimed.

The reed fabric with which my invention 25 is concerned is composed of a plurality of spaced members called stakes, which may be of reed or wire and which in workable lengths have sufficient rigidity to be self-supporting and to resist considerable force 30 tending to bend or kink abruptly. In this respect at least they differ greatly from the loose character of the threads of cloth which can be bent, twisted, or kinked in almost any manner with little force and without materially injuring them. Upon these stakes 35 long strands called fillers are woven over some of the stakes and under others. For example, the filler strand in some instances may pass over one stake and under the next adjacent stake, or it may pass over one stake and under the next two adjacent stakes, or it may vary in the manner in which it weaves under and over the stakes in a great many ways to produce different results and effects. 40 The reed fabric with which my invention is concerned is also to be distinguished from cane fabric such as is extensively used for chair seats and the like. While the filler strands may be and sometimes are put under 45 such tension as will gradually curve or shape

stakes, to the end that the finished fabric will have the desired form, the stakes are not usually abruptly bent or displaced by the filler strands, but on the other hand, the filler strands are bent and shaped to inter- 55 weave around stakes.

Reed is made in various sizes and in different cross-sectional shapes; it is tough and somewhat pliable and when woven presents an article which is of pleasing appearance 60 and of durable character. Furthermore, while the natural woody or fiber-like body of the reed presents an appearance that is really artistic, it may nevertheless, be readily tinted or painted in any desired manner. 65 Because of these inherent desirable qualities of the reed, articles made therefrom are extensively employed. In manufacturing reed articles, it has been the universal practice to weave the fabric free hand and for the reed- 70 worker to shape the article in the process of weaving to the desired form. If the article is one which must sustain considerable weight, or which is subject to heavy strains in use, such for example as a vehicle or an 75 article of furniture, it is customary to provide a rigid frame and to cover the frame with the reed fabric.

In weaving such articles as have a supporting frame, it has been hitherto customary to fasten the stakes in spaced relation to the article frame and then to weave the filler strands thereon. If the article is one that is irregular in shape, the stakes project at various angles. During the weaving operation, 80 under the hitherto universal practice, these stakes must be constantly shaped, positioned, and aligned, so that the fabric will assume the desired shape and also will have an appearance of uniformity and particularly to the 85 end that the stakes shall assume regular lines. The operation of weaving and shaping the reed fabric upon the article is a most difficult one because of these many variable factors and hence requires highly skilled 90 workmen, so much so that where there is any substantial amount of shaping, as is necessary under present methods in an article having pleasing curved lines, only workers 95 having several years of experience can be 100

employed and then the time required is considerable even to manufacture a relatively small article. As a result of the foregoing facts reed articles, while extensively used, 5 are at the present time expensive.

The general object of my invention is to provide a method wherewith it shall be possible to weave reed articles with greater rapidity and at lower cost than has hitherto 10 been possible.

Further objects of my invention are to provide a method of weaving reed articles in which many of the hitherto variable elements or factors shall be eliminated; where- 15 with artistic articles having curved or irregular lines can be produced with substantially the same ease as the straight, uniform, and simple articles; with which it shall be possible to weave the reed fabric with 20 greater uniformity and with increased strength; wherewith unskilled workers can produce reed articles of the kind hitherto producible only by the most skilled workmen; and wherewith the hitherto highly in- 25 dividualistic weaving of each reed fabric upon each article frame can be reduced to a factory system of weaving the reed fabric apart from the frame and in applying it thereto in a manner to secure desired shapes 30 and effects.

My invention consists generally in the manner, steps, acts, and sequence thereof, whereby the above named objects together with others which will appear hereinafter 35 are obtainable; and my invention will be more readily understood by reference to the accompanying drawings illustrative thereof, and wherein,

Figure 1, is a perspective view of an article frame upon which it is desired to provide a reed covering.

Fig. 2, is a side elevation of the frame shown in Fig. 1 but on a slightly enlarged scale.

Fig. 3, is a side elevation of a templet, guide, or form upon which I weave the fabric.

Fig. 4 is a plan view of the device shown in Fig. 3.

Fig. 5, illustrates the manner in which I weave the fabric.

Fig. 6, is a plan view of the mechanism shown in Fig. 5.

Fig. 7, is a detail of the fabric in the course of manufacture.

Fig. 8, is a cross-section of the fabric.

Fig. 9, is a detailed view substantially on the line 8-8 of Fig. 7.

Fig. 10, is a side elevation of the finished fabric, apart from the templet.

Fig. 11, is a plan view of the finished fabric.

Fig. 12, is a side view showing one step in the operation of securing the fabric to the article frame.

Fig. 13, is a view showing a further step in the operation of securing the fabric to the article frame.

Fig. 14, is a vertical transverse section of the finished article.

Figs. 17, 18, and 19 illustrate the method of giving different shapes, to the fabric on the article.

Figs. 15 and 16, illustrate a method of finishing the fabric edge.

Fig. 20, illustrates a strip of fabric which has been produced in endless form and severed to form a strip; and

Fig. 21, is a plan view of a type of frame to which the strip fabric shown in Fig. 20 can be applied.

For the purposes of illustration I have chosen to depict the manufacture of a baby carriage body because such articles, in the reed ware, are used extensively, and furthermore because such articles on the one hand fairly illustrate the difficulties encountered in the production of reed articles under the hitherto universal method, and on the other hand the ease and simplicity of manufacturing articles under my method.

In the drawings 1, illustrates the article frame which in this instance comprises a somewhat rectangular shaped upper member 2, and depending somewhat U-shaped side members 3, which in turn are connected by cross members 4, and 4'. In order better to understand the difficulties of weaving fabric upon the frame in the hitherto customary manner I shall first briefly describe that method. Under the former method the stakes are secured to the frame in spaced relation along the bottom portion of the side members 3, and along the cross members 4 and 4'. In order to secure the bowed or curved shape in the fabric, as shown in

Figs. 14, 17, 18, and 19, it has been necessary to fasten the stakes into the side portions of the frame so that they project substantially at right angles thereto. The reed workers having fastened the stakes in this position start at the bottom and weave the filler strand over and under the stakes, at the same time shaping the stakes upwardly and placing the filler strands under just the right tension so that the stakes can be gradually turned from their right angular positions progressively upward.

To shape these divergent stakes gradually upwardly, to maintain them in proper spaced relation, and to shape the filler strand with just that degree of tension necessary to give the desired shape and character to the fabric, is difficult indeed because of the many variable factors which must be considered and for which compensation must be made.

I might also state that in weaving reed in any form which is circular, spherical or partially so, there is a natural tendency for the reed to form in, that is to contract be- 130

yond the desired form or shape. This is probably due to the fact that the stakes are held at one end in desired alinement and when so secured cannot possibly move outwardly while the other end of the stakes are free and under the tension necessary to secure a tight weave are gradually and naturally pulled in. That is to say a novice weaving reed fabric could not weave it properly in such form, but it requires skilled weavers who understand thoroughly the action of the reed and who can counter-act the apparently naturally forming of the reed fabric to the extent necessary to give the fabric the desired shape.

I have solved this difficult complex problem in a very simple way by eliminating many of the variable factors and reducing the remaining ones to simple easily understood and easily manipulated steps. To this end instead of weaving the fabric upon the article frame which is usually of irregular shape, and which at best is poorly adapted for convenient weaving, I weave the fabric independent of the article frame in a convenient manner and then apply the finished woven fabric to and secure it upon the article frame. As will be better understood shortly in this way I secure freedom of movement and convenience in weaving which largely eliminate the present difficulties. Again I grip, space, and hold the stakes in such a way and in relation to a mechanical guide, templet, or form so that the most unskilled worker can weave the fabric by simply weaving in a natural manner around or against the templet or form. The templet is of such character that the fabric produced thereon will fit the desired frame, but the templet or form need not be of the same shape as the article to be covered as I find I can reshape the reed fabric after it is finished to admit covering article frames varying considerably in size, shape and character. In fact, I find that the weaving operation is greatly facilitated in many instances by weaving the fabric upon a circular or endless form or templet and then reshaping the finished reed fabric to elongated or such other shape as may be desired, or if necessary, cutting it for application to the frame.

In the drawings 5, represents a suitable templet upon which I weave the fabric and which in this instance comprises a lower annulus 6, and an upper annulus 7, between which are a plurality of members 8, which serve as guides, limiting devices, or restraining elements as will be hereinafter more fully described. It so happens in this instance that it is desirable that the side of the article shall take a gentle bow as indicated in Fig. 14, and for this reason I prefer to make the stakes and relation of the guides 8, in such a manner that a line con-

necting their peripheries would be curved or bowed. The templet 5, is preferably mounted for rotation, although this is a mere matter of convenience, upon a support 9, by any suitable means such for example, as the vertical shaft 10, which is secured centrally of the templet and which has a projecting portion entering a socket in the support. In the lower annulus 6, are a number of holes 11, suitably spaced in which the stakes 15, are placed and from which they upstand as illustrated in Figs. 5 and 6. These stakes it will be noted, upstand in regular form and encircle the templet guides 8. It is a most simple operation for the worker to weave the filler strands upon the stakes in this condition, it being but necessary to continue the filler strand or strands over and under the stakes and around the templet in regular courses from the bottom to the top, or conversely from the top to the bottom if desired, although I find it more convenient to work from the bottom upwardly. The filler strands are pulled so that the stakes just follow the guides 8, of the templet substantially as indicated in Fig. 9. The templet, therefore, so limits the movement of the stakes and the tension upon the filler strands that the fabric is naturally shaped to the form of the templet. The relatively close relation of the guides 8, prevents the stakes from being bent in beyond the desired point or line. In this manner an endless fabric having uniform courses of the filler strand can be produced rapidly by even an unskilled worker. The completed fabric is shown in Figs. 10 and 11 wherein 15, are the stakes and 16, the filler strands. In this instance I have left portions 17, of the stakes projecting from the body of the fabric at each end the purpose of which will be shortly described. To mount the woven fabric upon the article frame I apply pressure to the sides of the fabric thus producing a somewhat rectangular shape as indicated by the dotted line in Fig. 11. In this condition it can be easily placed over the article frame starting the large open end of the fabric over the bottom smaller end of the frame. Having placed the fabric upon the frame as indicated in the side view of Fig. 12 I fasten it to the ends of the frame in which condition it will be noted that the fabric projects upon the middle portion of the side members of the frame and does not quite extend to the lower portion. The reason for this is that the filler strands of the fabric are woven in regular progressive courses while the frame is curved or depressed in the middle. I have discovered, however, that I can readily shape the fabric to the frame by simply pulling upon it and also that the stakes serve as convenient handles for that purpose. I pull upon the 130

lower ends of the stakes until the lowermost 5 filler strands substantially coincide with the lower frame member at which time I secure the fabric in place by means of tacks, brads or other suitable fastening devices. By making the lower portion of the fabric follow the lower frame members the upper portion will generally follow the upper frame members as indicated in Fig. 13. In 10 this manner the uniform filler strand courses are made to assume the desired irregular course necessary to fit the article. It is immaterial whether or not a slight amount of the fabric projects above the 15 frame as it can be readily folded thereon. In fact in some instances I designedly provide sufficient fabric for that purpose. Thus it becomes evident that I can manufacture the fabric with the filler strands progressing 20 in regular courses and applying the finished fabric to an article, which if the fabric were woven thereon would require that the worker shape the strands irregularly and in non-parallel relation. At this time I might also 25 state that I can give varying degrees of curvature to the sides of the article body (cross-sectionally considered) by fastening the fabric along the bottom or top and pulling with greater or lesser force thus placing 30 the fabric under more or less tension. In Fig. 18 I have wrapped the fabric or folded it well over the frame members and have made it substantially taut therebetween. This gives but little curvature to the sides 35 and to secure a somewhat greater curvature I may proceed as indicated in Fig. 17 wherein I have illustrated the same fabric pulled with less force and wrapped a lesser distance around the frame which gives a greater 40 bow or more curvature to the fabric. Again I may secure a still greater bow or curvature by proceeding as indicated in Fig. 19. In this instance the fabric is not wrapped around frame members to any substantial 45 extent but is secured somewhat along the sides of the frame, thus placing all of the fabric between frame members and consequently giving it a greater bow or curvature with a resulting diminution in the tension. 50 In this way a number of different effects can be produced from a given fabric.

In Fig. 13, I have illustrated the reed simply applied to the article and before the projecting end portions of the stakes are 55 folded down to present a finished edge. There are many ways of finishing the edge of the fabric and I have illustrated but one way in Figs. 15 and 16. The portions 60 of the stakes are bent at right angles as indicated by the dotted line (See Fig. 15) each end portion passing over the next adjacent stake and behind the second one thus producing a finished edge 15, as shown in Fig. 16. Of course, I may so finish the edges of 65 the fabric before it is placed upon the frame

if desired, but I have so far found it more convenient to leave the projecting portions of the stakes and to finish them after they are placed upon the article.

It may be well here to note that in producing the article shown by the hitherto usual method, it is necessary to employ many short lengths which must be woven in places where the fabric departs from the general shape or uniform course, while by my novel 70 method the weaving can be done by full length strands serially woven in regular courses, or where the reed is procurable in endless form as, for example, paper reed, a single strand can be woven to complete the 75 entire fabric. A great saving in both time and material is thus effected. The tremendous advantages of this method will be obvious to those skilled in the art without further comment. 80

In qualifying the fabric or its elements as "reed" in the specification or claims, I mean to limit my invention to fabric the elements of which coöperate in the manner above described as characteristic of the stake 90 and strand fabric made of reed, but to embrace such materials whether they be the natural reed, paper reed, or other materials having the general characteristics of reed. 95

In the article thus far described the fabric 100 extends continuously around the frame but my novel method is not to be considered as limited to such form. For example, I can just as easily cover a U-shaped frame as shown in Fig. 21. To cover such a frame I 105 can proceed as already described to make an endless fabric and having produced the endless fabric cut it throughout its height thus producing a strip as indicated in Fig. 20. Such a strip can be readily secured to the 110 article frame and can be manipulated as described in reference to the first article to secure certain variation in the shape of the fabric and also in the course of the filler strand.

For some articles, templets, forms, or mechanical guides of different sizes, shapes and character will be employed, but my method will be found to be characterized by weaving the reed fabric in a manner convenient 115 for the weaving operation and when necessary or desirable reshaping and applying it to the article frame, as distinguished from the hitherto universal practice of weaving in a manner which is inconvenient, slow, 120 laborious and dependent upon a high degree of skill in the workman. With my method by providing relatively few templets of different sizes and shapes reed articles in great variety can be produced rapidly by unskilled 125 workers and at relatively low cost.

Inasmuch as this disclosure will readily suggest to others skilled in the art to which this appertains, various methods whereby the substantial objects of my invention can 130

be attained, I do not wish to be limited to the specific stated manner of procedure nor to the precise steps, acts, or stated sequence thereof, except only as may be necessary by limitations in the hereunto appended claims.

I claim—

1. The method of manufacturing reed articles having a frame and a reed fabric which consists in weaving the reed fabric in a shape different from the frame, reshaping the fabric out of its plane of weave, and attaching it to the frame. 10
2. The method of manufacturing reed articles having a frame and a tubular reed fabric which consists in weaving the reed fabric in tubular shape different from the frame, reshaping the fabric out of its plane of weave and attaching it to the frame. 15
3. The method of manufacturing reed articles having a frame and a reed fabric which consists in weaving the reed fabric about a templet in a shape different from the frame, reshaping the fabric out of its plane of weave and attaching it to the frame. 20
4. The method of manufacturing tubular reed articles having a frame and a reed fabric which consists in weaving the reed fabric in tubular form about a templet in a shape different from the frame, reshaping 25 the fabric out of its plane of weave and attaching it to the frame.
5. The method of manufacturing reed articles having a frame and a reed fabric which consists in weaving the reed fabric in a shape different from the frame, reshaping to conform to the frame in desired manner, folding marginal portions over the frame and attaching thereto. 30
6. The method of manufacturing tubular reed articles having a frame and a tubular reed fabric which consists in weaving a reed fabric in a shape different from the frame, shaping the fabric to conform to the frame in desired manner, and folding desired marginal portions over the frame and attaching the same thereto. 40
7. The method of manufacturing reed articles having a frame and a reed fabric which consists in weaving the reed fabric about a templet in a shape different from the frame, shaping the fabric to conform to the frame in desired manner, and folding desired marginal portions over the frame and attaching the same thereto. 50
8. The method of manufacturing tubular reed articles having a frame and a tubular reed fabric which consists in weaving the reed fabric about a templet in a shape different from the frame, shaping the fabric to conform to the frame in desired manner, folding desired marginal portions over the frame and attaching the same thereto. 55
9. The method of manufacturing tubular reed articles having a frame and a tubular reed fabric which consists in weaving the 60
- reed fabric apart from the frame, placing the woven fabric upon the frame, folding desired marginal portions over the frame and attaching the same thereto. 70
10. The method of manufacturing tubular reed articles having a frame and a tubular reed fabric which consists in weaving the reed fabric about a templet in tubular form apart from the frame, placing the woven fabric upon the frame, folding desired marginal portions over the frame, and attaching the same thereto. 75
11. The method of manufacturing reed articles having a frame and a tubular reed fabric which consists in weaving a tubular reed fabric having a contour curved with respect to its axis, at least in part, and having different cross sectional dimensions, reshaping the fabric out of its plane of weave and attaching it to the frame. 80
12. The method of manufacturing reed articles having a frame and a tubular reed fabric which consists in weaving a tubular reed fabric about a templet, the fabric having a contour curved with respect to its axis, at least in part, and having different cross sectional dimensions, removing the reed fabric, reshaping it out of its plane of weave and attaching it to the frame. 85
13. The method of manufacturing reed articles having a frame and a tubular reed fabric which consists in weaving a tubular reed fabric having a contour curved with respect to its axis, at least in part, and having different cross sectional dimensions, shaping the fabric out of its plane of weave to conform to the frame in desired manner, folding desired marginal portions over the frame and attaching the same thereto. 90
14. The method of manufacturing reed articles having a frame and a tubular reed fabric which consists in weaving, about a templet, a tubular reed fabric having a contour curved with respect to its axis at least in part, and having different cross sectional dimensions, shaping the fabric out of its plane of weave to conform to the frame in desired manner, folding desired marginal portions over the frame and attaching the same thereto. 95
15. The method of manufacturing reed articles having a frame and a tubular reed fabric which consists in weaving the tubular reed fabric having a contour curved with respect to its axis, at least in part, and having different cross sectional dimensions, placing the woven fabric upon the frame, folding desired marginal portions over the frame and attaching the same thereto. 100
16. The method of manufacturing reed articles having a frame and a reed fabric which consists in weaving the filler strands upon the stakes in substantially parallel relations, reshaping the fabric to cause a substantial part of the filler strands to assume non-par- 105
- 130

allel relations, at least in part, and attaching to the frame.

17. The method of manufacturing reed articles having a frame and a reed fabric which consists in weaving the filler strands upon the stakes in substantially parallel relations and about a templet, reshaping the fabric to cause a substantial part of the filler strands to assume non-parallel relations, at least in part, and attaching the fabric to the frame.

18. The method of manufacturing reed articles having a frame and a tubular reed fabric which consists in weaving the filler strands upon the stakes in substantially parallel relations, reshaping the fabric to cause a substantial part of the filler strands to assume non-parallel relations, at least in part, and attaching the fabric to the frame.

19. The method of manufacturing reed articles having a frame and a tubular reed fabric which consists in weaving the filler strands upon the stakes in substantially parallel relations and about a templet, reshaping the fabric to cause a substantial part of the filler strands to assume non-parallel relations, at least in part, and attaching the fabric to the frame.

20. The method of manufacturing reed articles having a frame and a tubular reed fabric which consists in weaving the filler strands upon the stakes in substantially parallel relations, and about a templet, reshaping the fabric to cause a substantial part of the filler strands to assume non-parallel relations, at least in part, placing the fabric upon the frame, folding desired marginal portions over the frame and securing same thereto.

21. The method of manufacturing reed

articles having a frame and a tubular fabric which consists in weaving the fabric to tubular form, distorting a substantial part of the fabric edgewise, at least in part, and attaching the distorted fabric to the frame. 45

22. The method of manufacturing reed articles having a frame and a tubular fabric which consists in weaving the fabric to tubular form apart from the frame, securing portions thereof to the frame, distorting 50 edgewise a substantial portion of the fabric which is unsecured, and securing distorted portions to the frame.

23. The method of manufacturing a non-circular reed article having a frame and a 55 reed fabric which consists in weaving the fabric about a circular templet into tubular shape, reshaping the fabric out of its plane of weave and permanently attaching it to the frame.

24. The method of manufacturing a non-circular reed article having a frame and a reed fabric which consists in weaving the fabric into circular shape, reshaping the fabric out of its plane of weave and permanently attaching the fabric to the frame. 65

25. The method of manufacturing reed articles having a frame and tubular fabric which consists in weaving the fabric to tubular form apart from the frame, distorting 70 the fabric while in tubular form and placing the distorted fabric upon and securing it to the frame.

In testimony whereof, I have hereunto set my hand, this 11th day of July, 1916, in 75 the presence of two subscribing witnesses.

MARSHALL B. LLOYD.
